UNITED STATES PATENT OFFICE.

WILLIAM OTTAWAY, OF AURORA, ILLINOIS, ASSIGNOR TO AURORA AUTOMATIC MACHINERY COMPANY, OF CHICAGO, ILLINOIS, A CORPORATION OF ILLINOIS.

CARBURETER.

1,135,046.

Specification of Letters Patent. Patented Apr. 13, 1915.

Application filed January 31, 1913. Serial No. 745,318.

To all whom it may concern:

Be it known that I, WILLIAM OTTAWAY, a citizen of the United States, and a resident of Aurora, in the county of Kane and State of Illinois, have invented certain new and useful Improvements in Carbureters; and I do hereby declare that the following is a full, clear, and exact description thereof, reference being had to the accompanying drawings, and to the letters of reference marked thereon, which form a part of this specification.

This invention relates to that class of carbureters which are adapted to be used in connection with internal combustion engines or motors, and more especially to the means for controlling and regulating the proportion of air and combustible fluid or hydrocarbons to be intermixed.

The principal object of the invention is to provide a simple, economical and efficient carbureter.

Other and further objects of the invention will appear from an examination of the following description and claims and from an inspection of the accompanying drawings.

A carbureter of the construction herein shown and described is adapted to enable the admission of high-speed air and low-speed air to be controlled by separately adjustable means, and to enable the proportion of air and hydrocarbons under high-speed and low-speed conditions, respectively, to be controlled and regulated by controlling and regulating the air supply by such separately adjustable means.

The invention consists in the features, combinations, and details of construction herein described and claimed.

In the accompanying drawings, Figure 1 is a view in central vertical section of a carbureter constructed in accordance with my improvements, the portion through the parts shown in Fig. 2 being taken on irregular line 1 of Fig. 2 and the remaining portion being taken through the center of the device, as indicated by sectional line 3 of Fig. 3; Fig. 2, a horizontal sectional view, taken on line 2 of Fig. 1; Fig. 3, a horizontal sectional view, taken on line 3 of Fig. 1; Fig. 4, a horizontal sectional view, taken on line 4 of Fig. 1; Fig. 5, a detail view in central vertical section through the center of the rotative valve mechanism and

mixing chamber, showing the throttle valve and connecting rod in elevation; Fig. 6, a detail plan view of the throttle valve or butterfly valve shown in Figs. 1 and 5, showing the throttle valve bushing or casting in section; and Fig. 7, an enlarged detail view of the portion of the feed tube or nozzle shown in Fig. 1.

In constructing a carbureter in accordance with my improvements, I provide a casing *a* having an inner tubular portion or inner casing walls *b* encircled by the outer casing or walls and forming therewith an annular float chamber *c* in which is located an annular float *d*. The float is, by preference, in the form of a hollow, annular shell which encircles the inner casing portion *b*, and is encircled by the outer casing *a* and adapted to move freely upward and downward within the casing or float chamber. An annular bottom casing member or portion *e*, which is, by preference, made in one integral piece with the outer casing portion or walls *a*, forms the main bottom of the casing and float chamber and is provided with an upwardly extending, screw-threaded flange *f* in screw-threaded engagement with the screw-threaded bottom end of the inner casing member or tube *b*, as shown in Fig. 1. A cover *g* of annular construction encircles the upper portion of the inner casing or tube member *b* and is secured thereto and to the outer casing member *a* in any desired suitable manner. The upper portion *h* of the inner casing or tube *b* projects through and upward beyond the cover member *g* and is provided with outer screw threads as indicated in Fig. 1. An upper casing or neck member *i* of tubular construction and having an elbow portion *j* is connected with the main casing, and forms an outlet passage leading from the mixing chamber or space. This casing member *i* has inner screw threads at its lower end in threaded engagement with the upwardly projecting portion *h* of the inner casing member or tube *b*, and is provided with means for operatively connecting the carbureter with the fuel supply pipe of an engine or motor, which connecting means may be in the form of a nipple or sleeve *k* and a pipe coupling *l* having inner screw threads *m*, for engaging the threaded end of a fuel supply pipe or conduit leading to the motor or engine cylinder.

der. A feed tube *n* forming a combustible fluid or hydrocarbon supply passage *o*, is mounted in position to extend upwardly on the inside of the inner casing member or tube *b* and is supported by means of a supporting member or tube body portion *p* having radial arms *q* which are secured to the casing bottom *e* by means of screws *r* or other similar securing means, and a casing bottom member or sub-bottom *s* having side wall portions *t* is mounted beneath the annular casing bottom member *e* and provided with a central aperture through which the lower end of the feed tube may project. The lower projecting end *u* of the feed tube is provided with inner and outer screw threads, and a nut *v* is mounted in threaded engagement with the outer screw threads of this downwardly projecting end portion of the feed tube and in supporting engagement with the bottom member *s* so as to securely hold the tube and said bottom member in position and in rigid engagement with each other.

25 A plug *w* is mounted in threaded engagement with the bottom end of the tube and forms a closure for the same. The bottom member *s* with its side walls *t* forms an air reservoir passage or space *y*, and is provided with one or more air supply passages *z* communicating with said space. A suitable screen *2* of reticulated material or wire netting is mounted on the interior of the passage, reservoir, or compartment *y* in position to admit air to and exclude dust, sand, grit, and other foreign substances from the interior of the carburetor or mixing chamber. A hollow tubular portion *3* is provided in one side of the casing having a passage *4* through the inner wall thereof which communicates with the interior of the float chamber *c*, as shown in Fig. 1. The upper end of this vertical, tubular portion is closed by means of a plug *5*. To the lower end of the tubular portion *3* is secured a coupler member or valve casing *6*, the upper end of which is in threaded engagement with the tubular member *3*, and the lower portion of which is provided with screw threads and adapted to be secured in threaded engagement with a suitable coupler member or supply pipe connected with a source of hydrocarbon or combustible fluid supply. The coupler member *6* or valve casing *6* has a central, axial opening or passage *8* leading therethrough, and mounted in this passage is a movable valve member or valve plunger *9* having a conical lower end portion *10* movable into and out of engagement with a similar conical valve seat portion *11*, said valve seat portion being immediately above a restricted portion *12* of the passage *8*. A valve-operating lever *13* is pivotally mounted upon a suitable supporting member or bracket *14* by means of a horizontal pivot *15*, and is provided with forked lever arms *16* located on the inside of the float chamber and extending on opposite sides of the inner casing member or tube *b*, each of said arms having their forked end portions in engagement with the bottom of the float *d*. The supporting bracket *14* which supports the valve-operating lever *13* is secured in position by means of a screw *17* and nut *18*, as shown in Fig. 1, or by any desired suitable securing means, and the lever *13* is provided with an opening *19* through the end portion of said lever, which is located in the interior of the tube *3* and through which perforation the valve body *9* extends. The lever *13* is thus adapted to be operated by the float *d*, and to operate the vertically movable valve body or valve member *9*, as the liquid admitted to the float chamber causes the float to rise or descend. The valve body is provided with one or more longitudinal passages *20* therein which are adapted to be opened when the valve body is raised and to be closed when the valve body is lowered or in engagement with the valve seat. Connected with the upper end of the valve body and vertically movable in the tube *3* is a cylindrical member *21* which is adapted to form a counter-weight for holding the valve member *9* removably in engagement with the valve seat, and adapted to permit the valve to be raised by means of the float *d* and valve-operating lever when the hydrocarbon or combustible fluid becomes sufficiently low in the float chamber to permit the float to so operate the lever *13* as to raise the valve and the counter-weight *21*. The lower end of this cylindrical member *21* is provided with a vertical, axial perforation into which the valve member *9* extends, and is thus adapted to be adjustably secured in threaded engagement with the valve member *9*, and when so secured it is adapted to enable the valve member *9* to be adjusted up or down. But with needle valve member *9* without threads and merely pressed into weight *21*, the bending of lever *13* will enable the proper seating of the valve to be obtained and the height of gasoline in the float chamber to be varied. The float chamber is provided with an outlet opening *22* which is covered by a screen *23*. This opening communicates with the inner passage *o* in the feed tube *n* by way of a passage *24* formed by a tube *25*, one end of which is connected with the feed tube *n* and the other end of which is connected with the bottom of the casing and float chamber outlet *22* by means of a coupler member or screened cap and pipe-connecting member *26*. The screen-supporting cap *26* and pipe *25* thus form a passage leading from the float chamber to the interior of the feed tube *n*. The feed tube *n* is pro-

vided at its upper end with a plug 27 having a conical head which fits in a conical seat in the upper end of the tube, the conical head of the plug being provided with a plurality of peripheral grooves forming passages 28 which communicates with the interior of the feed tube and with the carbureting chamber or space above the feed tube hereinafter more particularly described. The plug 27 is provided with a screw threaded portion 29 which is in threaded engagement with the feed tube. The plug has an axial opening 30 therein and is provided with a non-threaded restricted peripheral portion 31 which is of less diameter than the portion of the tube *n* which encircles the same, thus forming an annular space 32 between said non-threaded portion of the plug and the inner wall of the tube. The space 32 is connected and communicates with the axial opening 30 by means of passages 33, as shown in Fig. 7, and communicates with the mixing chamber or interior space above the plug or nozzle 25 through the passages 28, as shown in Fig. 1.

A throttle valve, which is, by preference, in the form of a butterfly valve 34, is rockingly mounted in the upper portion *i* of the casing upon a horizontal rock-shaft 35 which is journaled or rotatably supported in the casing and provided at its outer end with an operating lever arm or crank 36 (see Figs. 1, 5 and 6). This throttle valve is adapted to be automatically operated or turned to an opened or closed or any desired intermediate position to correspond with the speed of operation of the motor or engine in any desired, ordinary, or known manner and by means of operating mechanism of any desired type known to those skilled in the art. The throttle valve shown in the drawing is provided with a restricted opening or openings 37 which may be of any desired form, adapted to permit the passage of combustible fluid from the mixing chamber or space 38 to the motor or engine when the latter is running at low speed with the throttle valve in closed position.

An upwardly and downwardly tapered air-receiving tube 39 having an upper end portion 40 of less diameter than the lower portion encircles the feed tube *n* and forms a tapered, annular air passage 41 which communicates with the air-containing space 42 below the carbureting chamber or space 38, and forms a conduit the upper end of which is, by preference, slightly below the level of the top of the nozzle and adapted to conduct a current of air upward on all sides of and adjacent to the nozzle in such a manner that the air is caused to flow upward past the nozzle and become thoroughly intermixed with the liquid hydrocarbon passing from the nozzle in the same general upward direction. An inner tubular valve member

or bushing 43 extends upward from a point preferably slightly below the top of the nozzle in position to encircle the nozzle, and has its upper end portion 44 in bearing engagement with the neck or casing portion *i*. This cylindrical or tubular bushing member is of less diameter than the stationary inner tube or casing member *b*, and forms an air space 45 between said rotative bushing member and said tube *b*. The tubular member 43 is provided at its lower end with radially projecting prongs or supporting and guiding lugs 46—shown in Figs. 1 and 3—which are adapted to guide and support the lower end of the tubular member 43 rotatively in upright position in concentric relation to the casing portion *i* and the feed tube *n*. The cylindrical, rotatively mounted valve member or bushing 43 is provided with a series of air-inlet openings 47 (see Fig. 3) which are adapted to be moved into and out of position to register with the corresponding openings 48 in an inner cylindrical, rotative and endwise movable cylindrical valve member 49 hereinafter more particularly described. The rotative, cylindrical valve member or bushing 43 is provided with an operating stem 50, the inner end 51 of which is in screw-threaded engagement with said rotative valve member or bushing. This stem is for rotating the valve member 43 for controlling the admission of high-speed air and extends through a radial, segmental slot 52, shown in Figs. 1 and 2 of the drawings, which is adapted to permit the movement of the operating stem in a horizontal plane in the operation of rotating the cylindrical valve member or bushing 43 with respect to the inner, tubular, cylindrical valve member 49, for the purpose of increasing or decreasing, or controlling and regulating the size or effectual area of the openings 48 which communicate with the air space 45 on the outside of the tubular members 43 and 49 and with the mixing chamber or inner air spaces on the inside of said tubular members. Segmental, curved guides 53 and 54 formed of flexible material and the inner one of which has a curved inner surface adapted to slidably engage the outer cylindrical surface of the casing member *i*, extend across the opening 52 in the casing member *i*, and are secured to and movable with the stem 50 so as to keep the opening 52 constantly closed during the movement of the operating stem or when the stem is in any desired position to which it is adapted to be adjusted. A nut or stop block 55, shown in Fig. 2, is adapted to stop the operating stem 50 at the opposite extremities of its movement, respectively, by engaging the respective marginal walls of the slot 52.

The inner, rotative and endwise movable valve member or sleeve 49 is provided with a downwardly and inwardly tapered cone 130

shaped lower portion 56, the inclined wall portions of which have openings 57 therebetween, as shown in Fig. 3. These openings are, by preference, normally slightly 5 below the top of the nozzle 27 and intermediate the lower end of the rotative cylindrical valve member or bushing 43 and the end of the nozzle, and a cylindrical washer 58 having a radial, annular flange 59 is 10 mounted at the bottom end of the conical inner tubular valve member 49 below the openings 57 and, by preference, secured to and movable upward and downward with the tubular valve member 49 so as to decrease 15 the size of the opening 60 between the flange 59 and the lower end of the cylindrical valve member or bushing 43, when the inner valve member 49 is raised, and increase the size of said opening, when the valve 20 member 49 is lowered. The washer 58 may be mounted in fixed engagement with and in position to encircle the tapered, tubular member 39, above described, and the tapered, tubular member 39 is, by preference, secured 25 to and movable upward and downward with and supported by the conical inner cylindrical valve member 49. The cylindrical valve member 49 is, in turn, supported by a connecting rod or plunger 61 the lower end of 30 which is pivotally connected with said cylindrical valve member 49 by means of a horizontal pivot or shaft 62 (see Figs. 1, 2 and 5), and the upper end of which is operatively connected with the throttle valve 35 by means of lugs 63 which are secured to the valve 34 and a horizontal pivot 64 mounted in said lugs and in pivotal supporting engagement with the plunger or connecting rod 61 which is provided with perforations 40 in its upper end through which said pivot extends.

It is desirable to provide means for regulating and controlling the admission of low-speed air or air for use when the apparatus 45 is being operated under low-speed conditions adapted to be adjusted independently of the means for regulating the high-speed air. In order to accomplish this the cylindrical valve member or bushing 43 is provided with a radial opening 65 and the inner, tubular, cylindrical valve member 49 is provided with a corresponding opening 66, best shown in Figs. 1 and 2, which are adapted to register when the throttle valve 50 is closed and the inner cylindrical valve member 49 in its raised or uppermost position, and to be closed when the throttle valve 55 is open and the inner, tubular member 49 in its lowermost position. The casing portion is 60 provided with an air-inlet opening 67 and a rotative valve 68 is mounted in the opening or passage 67 and adapted to open and close the same and to regulate the volume of air admitted therethrough. This valve 65 68 is provided with a thumb nut 69 (see

Figs. 1 and 2) by means of which it is adapted to be operated, and is shown in closed position in Figs. 1 and 2, the peripheral body portion of the valve being in position to extend across the opening 67 and the passage 70 in the valve being closed. An inner sleeve or bushing 71 is mounted in the bottom portion of the tubular member 49, for restricting the size of the passage and deflecting the air inward toward the nozzle. 75

From the foregoing description it will be seen that the passage 41 in the tapered sleeve 39 is at all times adapted to admit air to the carbureting chamber, and that the opening 60 between the flange 59 and the bottom of the cylindrical valve member or bushing 43 is wide open and adapted to co-act with the openings formed by the ports 47 and 48 when the throttle valve 34 is in open position, under which conditions the opening through ports 47 and 48 and the opening 60 are adapted to admit air in suitable quantities for high-speed conditions and the carburetor is adapted to supply a mixture of air and hydro-carbons to a motor operating at high-speed. 80

In operation the cylindrical bushing or valve member 43 is rotated to any desired adjusted position by means of the stem 50 for the purpose of adjusting or increasing or diminishing the width of the openings formed by the ports 47 and 48, thereby regulating the proportion of air and vapor or hydro-carbons admitted for or during the operation of the device under high-speed conditions. The proportion of air and vapor or hydro-carbons entering the mixing chamber under low-speed conditions is regulated and controlled by the adjustment 95 of the valve 68 to increase or diminish the area of the opening 67, as already described. The valve 68 and the rotative valve casing or bushing member 43 are thus separately adjustable for the purpose of controlling and regulating the proportion of air and vapor or hydro-carbons admitted under high-speed and low-speed conditions, respectively. 100

Assuming the ports 47 and 48 for regulating the admission of auxiliary air for high-speed and the ports 65 and 66 for regulating the proportion of air and vapor for low-speed conditions to have been adjusted so that said ports are of the desired 115 width, and that the throttle valve is adapted to be manually opened and closed in a manner which will vary the size of the outlet in proportion to the speed of the motor, the operation of the parts is as follows: The cylindrical valve member 49 is moved endwise in the valve bushing 43 by the operation or partial rotation of the valve 34 as the latter is operated, for the purpose of controlling the quantity of mixture deliv- 120 130

ered to the motor. The endwise movement of said cylindrical valve member causes the main air inlet port or opening 60 to be opened or enlarged to correspond with the extent of the opening of the valve 34, and closed or diminished to correspond with the closing of the latter, thereby enabling the supply of air passing into the mixing chamber adjacent to the nozzle to be varied to correspond with the quantity of mixture delivered to the engine. The endwise movement of the inner cylindrical valve member 49 in one direction—for instance downward in a device constructed as herein shown and described—causes the auxiliary air inlet openings formed by the ports 47 and 48 for admitting high-speed air to be opened or enlarged, and causes the air inlet openings formed by the ports 65 and 66 for admitting low-speed air to be closed or diminished. The closing or diminishing of the size of the openings formed by the ports 65 and 66 begins as the ports 47 and 48 begin to be opened, and the ports 65 and 66 are entirely closed when the ports 47 and 48 for high-speed are entirely opened. It follows, as a matter of course, that the endwise movement of the inner cylindrical valve member 49 in the opposite direction will occur with the movement of the valve 34 to or in the direction of closed position, thus causing the main air supply opening or port 60 at the bottom of the cylindrical or tubular valve members 43 and 49 to be diminished or closed in proportion to the extent of movement of the valve 34 to or in the direction of closed position. The annular space 45 between the rotative tubular valve member 43 and the inner annular wall *b* of the casing 40 may be said to form an auxiliary air inlet passage for high-speed air, said passage being adapted to communicate with the interior of the mixing chamber when the coacting ports 47 and 48 in the rotative tubular valve member 43 and endwise movable, tubular valve member 49 are open. The effectual area of the auxiliary air inlet passage formed by the space 45 and the coacting ports 47 and 48 is therefore varied, or increased and diminished for the purpose of regulating the proportion of hydro-carbons and high-speed air by the circumferential adjustment or rotation of the rotative valve member 43 with respect to the endwise movable, tubular valve member 49, as above suggested. The endwise movement of the inner cylindrical or tubular valve member 49 upward or in a direction tending to close the ports 47 and 48 and the main air inlet port 60 causes the inlet opening formed by the ports 65 and 66 to be opened or increased for admitting auxiliary low-speed air. When the opening 60 and the ports 47 and 48 have thus been entirely closed, the ports 65 and 66 for low-speed air will be entirely open and the tapered annular passage 41 will also still be open so that air will be admitted through the passage 41 and adjacent to the nozzle *n* with sufficient rapidity of movement to be thoroughly intermixed with the combustible fluid or liquid hydro-carbons, when the device is in operation under low-speed conditions.

The carbureter above described is thus adapted to enable the desired proportions of hydro-carbons and air to be admitted and thoroughly intermixed, under varying high-speed and low-speed conditions, respectively, and to enable the proportions of air and hydro-carbons under both high-speed and low-speed conditions to be varied and regulated or controlled by regulating the admission of air, and without the necessity of regulating or changing the hydro-carbon supply nozzle or passages. The auxiliary passages for high-speed air and the auxiliary passages for low-speed air are controlled and the proportion of hydro-carbons and air under high-speed and low-speed conditions, respectively, are regulated by means of separately adjustable valve members or devices, and the operation of the endwise movable, tubular valve member is such as to control or vary the effectual area of the main air inlet passage and the auxiliary air inlet passages for both high-speed air and low-speed air, with such separately adjustable valve members in any position to which they are adapted to be adjusted.

It will be readily understood by those skilled in the art that although the downward movement of the inner cylindrical valve member opens the auxiliary high-speed air inlet passages and main air supply passages leading to the mixing chamber and closes the low-speed auxiliary air passage, the positions and relations of the coacting auxiliary ports for low-speed and high-speed air, respectively, may readily be reversed, so that the downward movement of the endwise movable, tubular valve member will act to close the passages for high-speed air and open the ports or passages for low-speed air without departing from the spirit of this invention.

It is manifest that the details of construction in an apparatus containing the general features herein set forth may be variously modified in practice without departing from the spirit of my invention, and I do not, therefore, desire to be limited to the particular features and details of construction illustrated or described, except in so far as the same may be pointed out in the appended claims.

I claim:

1. In a carbureter, the combination of a casing provided with a mixing chamber having main air-inlet and mixture-outlet openings and provided with auxiliary inlet pas-

- sages adapted to communicate with the mixing chamber, independently adjustable valve members for each of said auxiliary inlet passages acting to control the effective areas 5 of said auxiliary air-inlet passages, a reciprocating valve member adapted to simultaneously open one and close the other of said auxiliary inlet passages, with said separately adjustable valve members in any desired 10 adjusted position, a movable valve member in engagement with the mixture-outlet port, and an operating lever operatively connected with the valve member for the mixture-outlet port and with said reciprocating valve member.
2. In a carbureter, the combination of a casing provided with a mixing chamber having main air-inlet and mixture-outlet openings and provided with an auxiliary inlet 15 passage for high-speed air and a separate auxiliary inlet passage for low-speed air, each of said auxiliary inlet passages being adapted to communicate with the mixing chamber, and a reciprocating valve member 20 adapted to simultaneously open one and close the other of said auxiliary air passages.
3. In a carbureter, the combination of a casing provided with a mixing chamber having main air-inlet and mixture-outlet openings and provided with independent auxiliary air inlet passages adapted to communicate with the mixing chamber, independently adjustable valve members mounted in the casing and adapted to vary the effective 25 areas of said auxiliary inlet passages, a throttle-valve mounted in said casing adapted to control the discharge of the mixture from said mixing chamber, and a valve member movable with said throttle-valve and independently 30 of said valve members for opening and closing said auxiliary air-inlet passages, and adapted to simultaneously diminish the passage of air through one and increase the passage of air through the other 35 of said auxiliary passages, as the discharge of mixture through the outlet port is decreased or increased.
4. In a carbureter, the combination of a casing provided with a mixing chamber having 40 main air-inlet and mixture-outlet openings and provided with an auxiliary inlet passage for high-speed air and a separate auxiliary inlet passage for low-speed air, each of said auxiliary passages being adapted 45 to communicate with the mixing chamber when the other of said passages is closed, separately adjustable rotative valve members mounted in the casing, one of said rotative valve members being adapted to vary the 50 effectual area of the auxiliary inlet passage for high-speed air, and the other of said rotative valve members being mounted in position to vary the effectual area of the auxiliary inlet passage for low-speed air, 55 and an endwise movable tubular valve member

mounted in sliding engagement with one of said rotative valve members, and means for reciprocating said endwise movable valve member, for increasing and diminishing the effectual area of said auxiliary air-inlet 70 passages, with said separately adjustable rotative valve members in any position to which they are adapted to be adjusted.

5. In a carbureter, the combination of a casing provided with a mixing chamber 75 having main air-inlet and mixture-outlet openings and provided with an auxiliary inlet passage for low-speed air adapted to communicate with the mixing chamber, a rotative valve member mounted in the casing in position to coact with the auxiliary inlet passage for low-speed air for varying the effectual area of said passage, a rotative tubular valve member, and an endwise movable tubular valve member mounted in sliding engagement with each other and provided with coacting auxiliary inlet ports adapted to form an auxiliary inlet opening for high-speed air, means for adjusting the rotative tubular valve member, for varying 80 the effectual area of the passage formed by said coacting ports for the admission of high-speed air, and means for reciprocating the endwise movable tubular valve member, for varying the effectual area of all of said 85 auxiliary inlet openings.

6. In a carbureter, the combination of a casing provided with a mixing chamber having main air-inlet and mixture-outlet openings and provided with an auxiliary inlet 90 passage for low-speed air adapted to communicate with the mixing chamber, a rotative valve member mounted in the casing in position to coact with the auxiliary inlet passage for low-speed air for varying the effectual area of said passage, a rotative tubular valve member and an endwise movable tubular valve member mounted in sliding engagement with each other and provided with coacting auxiliary inlet ports 95 adapted to form an auxiliary inlet passage for high-speed air, means for adjusting the rotative tubular valve member, for varying the effectual area of the opening formed by said coacting ports for the admission of high-speed air, a movable outlet valve member mounted in the mixture-outlet passage, means for operatively connecting said outlet 100 valve member with the endwise movable tubular valve member, and a manually operable lever connected with the outlet valve member, for operating said outlet valve member and the endwise movable tubular valve member.

7. In a carbureter, the combination of a 105 main casing, a pair of tubular valve members mounted in the main casing in concentric relation and provided with main air-inlet and mixture-outlet openings, said valve members having coacting auxiliary air-inlet 110

- ports adapted to communicate with each other and with the space surrounded by said valve members, one of said tubular valve members being rotative to different adjusted positions with respect to the other valve member, for changing the effectual area and width in one direction of the opening formed by said coacting auxiliary ports, and the other of said tubular valve members being movable endwise in opposite directions to different adjusted positions to change the size of the opening formed by said coacting auxiliary ports in a direction lengthwise of the tubular valve members.
8. In a carbureter, the combination of a main casing, a pair of tubular valve members mounted in the main casing in concentric relation and provided with main air-inlet and mixture-outlet openings, said valve members having coacting auxiliary air-inlet ports adapted to communicate with each other and with the space surrounded by said valve members, one of said tubular valve members being rotative to different adjusted positions with respect to the other valve member, for changing the effectual area and width in one direction of the opening formed by said coacting auxiliary ports, and the other of said tubular valve members being movable endwise in opposite directions to different adjusted positions to change the size of the opening formed by said coacting auxiliary ports in a direction lengthwise of the tubular valve members, and means for moving the endwise movable tubular valve member longitudinally of the rotative valve member to different adjusted positions.
9. In a carbureter, the combination of a main casing, a pair of tubular valve members mounted in the main casing in concentric relation and in sliding engagement with each other and provided with main air-inlet and mixture-outlet openings, said valve members having coacting auxiliary air-inlet ports adapted to communicate with each other and with the space surrounded by said cylindrical valve members, one of said cylindrical valve members being rotative to different adjusted positions with respect to the other valve members, for changing the effectual area of the opening formed by said coacting ports, and the other of said tubular valve members being movable endwise in opposite directions, to change the size of the passage formed by said coacting ports in a direction lengthwise of the tubular valve members, valve mechanism for opening and closing the mixture-outlet opening, and manually operable reciprocating mechanism connected with the endwise movable cylindrical valve member for moving the same endwise in opposite directions.
10. In a carbureter, the combination of a main casing, a pair of tubular valve members mounted in the main casing in con-
- centric relation and provided with main air-inlet and mixture-outlet openings, said valve members having coacting auxiliary air-inlet ports forming an inlet passage for high-speed air, adapted to communicate with the space surrounded by said tubular valve members, one of said tubular valve members being rotative to different adjusted positions with respect to the other, for changing the area of the opening formed by said communicating ports, and the other of said tubular valve members being movable endwise in opposite directions to open and close said main and auxiliary inlet ports, a throttle valve operatively connected with the endwise movable tubular valve member and adapted to be moved toward its open position with the movement of said endwise movable tubular valve member toward the position which it occupies when the main air inlet is open, and means for operating the throttle valve and endwise movable tubular valve member simultaneously, in one direction to open the throttle valve and main air-inlet passage, and in an opposite direction to close said main air-inlet and throttle valve, and open the auxiliary air-inlet passage for high-speed air.
11. In a carbureter, the combination of a main casing, a pair of tubular valve members mounted in the main casing in concentric relation and provided with main air-inlet and mixture-outlet openings, said valve members having adjacent auxiliary air-inlet ports adapted to communicate with each other and with the space surrounded by said tubular valve members, one of said tubular valve members being rotative to different adjusted positions with respect to the other valve member, for changing the effectual area and width of the opening formed by said communicating ports, and the other of said cylindrical valve members being movable endwise in opposite directions to increase and diminish the size of the opening formed by said auxiliary air-inlet ports in a direction lengthwise of the tubular valve members, a rotary throttle valve, a link having one end connected with the rotary throttle valve and having its opposite end connected with the endwise movable tubular valve member, and means for operating the throttle valve.
12. In a carbureter, the combination of a main casing, a pair of tubular valve members mounted in the main casing in concentric relation and sliding engagement with respect to each other and provided with main air-inlet and mixture-outlet openings, said valve members having adjacent auxiliary air-inlet ports adapted to communicate with each other and with the space surrounded by said tubular valve members, one of said tubular valve members being rotative with respect to the other, for changing

the area of the opening formed by said communicating ports, and the other of said tubular valve members being movable endwise in opposite directions to open and close said auxiliary communicating ports, a throttle valve movable to open and close positions, and means for moving the endwise movable tubular valve in opposite directions alternately simultaneously with the movement of the throttle valve toward open and closed positions, respectively.

13. In a carbureter, the combination of a main casing, a pair of hollow cylindrical valve members mounted in the main casing in concentric relation and forming the annular walls of a mixing chamber provided with main air-inlet and mixture-outlet openings, said valve members having adjacent auxiliary air-inlet ports adapted to communicate with each other and with the space encircled by said cylindrical valve members, one of said cylindrical valve members being rotative with respect to the other, for changing the area of the opening formed by said communicating auxiliary air-inlet ports, and the other of said valve members being movable endwise in opposite directions to open and close said auxiliary ports, and means upon the endwise movable cylindrical valve member for opening and closing the main air-inlet opening of the mixing chamber.

14. In a carbureter, the combination of a main casing a pair of hollow tubular valve members mounted in the main casing in concentric relation and forming adjustable annular walls of a mixing chamber having a mixture-outlet opening, said tubular valve members having coacting openings at their lower ends forming a main air-inlet passage and having adjacent auxiliary air-inlet ports intermediate the main air-inlet passage and mixture-outlet passage, adapted to communicate with each other and with the space encircled by said tubular valve members, one of said tubular valve members being rotative with respect to the other, for changing the area of the opening formed by said communicating auxiliary air-inlet ports, and the other of said valve members being movable endwise in opposite directions to open and close said auxiliary ports and main air-inlet passage, and an annular flange upon the endwise movable tubular valve member adapted to open and close the main air-inlet passage.

15. In a carbureter, the combination of a main casing, a pair of hollow tubular valve members mounted in the main casing in concentric relation and forming adjustable annular walls of a mixing chamber having a mixture-outlet opening, said tubular valve members having coacting openings at their lower ends forming a main air-inlet passage, adapted to communicate with each other and with the space encircled by said tubular

valve members, one of said tubular valve members being rotative with respect to the other, for changing the area of the opening formed by said communicating auxiliary air-inlet ports, and the other of said valve members being movable endwise in opposite directions to open and close said auxiliary ports and main air-inlet passage, a nozzle having a combustible fluid supply passage communicating with the mixing chamber, a depending tubular end portion on the inner tubular member encircling the nozzle and forming an air-inlet passage between the nozzle and the main air-inlet passage of the mixing chamber, and an annular flange upon said depending tubular portion of the inner valve member for controlling the effectual area of the main air-inlet opening.

16. In a carbureter, the combination of a main casing, a pair of hollow tubular valve members mounted in the main casing in concentric relation and forming adjustable annular walls of a mixing chamber having a mixture-outlet opening, said tubular valve members having coacting openings at their lower ends forming a main air-inlet passage, adapted to communicate with each other and with the space encircled by said tubular valve members, one of said tubular valve members being rotative with respect to the other, for changing the area of the opening formed by said communicating auxiliary air-inlet ports, and the other of said valve members being movable endwise in opposite directions to open and close said auxiliary ports and main air-inlet passage, a nozzle having a combustible fluid supply passage communicating with the mixing chamber, a depending tubular end portion on the inner tubular member encircling the nozzle and forming an air-inlet passage between the nozzle and the main air-inlet passage of the mixing chamber, an annular flange upon said depending tubular portion of the inner valve member for controlling the effectual area of the main air-inlet opening, and manually operable mechanism for moving the inner tubular valve member endwise in opposite directions successively to different adjusted positions.

17. In a carbureter, the combination of a main casing, a pair of hollow tubular valve members mounted in the main casing in concentric relation and in sliding engagement with each other and provided with main air-inlet and mixture-outlet openings, said valve members having adjacent auxiliary air-inlet ports adapted to communicate with each other and with the space surrounded by said valve members, one of said tubular valve members being rotative with respect to the other, for changing the effectual area of the opening formed by said communicating ports, and the other of said tubular valve members being movable endwise in opposite

directions to open and close the main air-inlet passage and said auxiliary communicating ports, a throttle valve for the mixture-outlet-passage movable to open and closed positions, and manually operable mechanism 5 acting to move the endwise tubular valve member toward the position which it occupies when the main air-inlet passage is open, simultaneously with the movement of the 10 throttle valve toward open position, adapted to move said endwise movable tubular valve member in an opposite direction to close said main air-inlet passage simultaneously with the movement of the throttle valve to closed position.

18. In a carbureter, the combination of a main casing, a pair of tubular valve members mounted in the main casing in concentric relation and in sliding engagement with 20 each other and forming the annular walls of a mixing chamber provided with main air-inlet and mixture-outlet openings, said valve members having coacting auxiliary air-inlet ports adapted to communicate with 25 the mixing chamber, one of said tubular valve members being rotative with respect to the other for changing the width and effectual area of the opening formed by said communicating auxiliary ports, and the other 30 of said tubular valve members being movable endwise in opposite direction to open and close the passage formed by said coacting auxiliary ports, a nozzle having a fluid supply passage communicating with the mixing 35 chamber, a throttle valve for opening and closing the mixture-outlet opening, a link having one end pivotally connected with the endwise movable tubular valve member and having its opposite end pivotally connected with said throttle valve, means for operatively connecting the mixture-outlet opening with the cylinder of an 40 engine, and manually operable means for moving the throttle valve toward and from 45 open and closed positions.

19. In a carbureter, the combination of a main casing, a pair of tubular valve members mounted in the main casing in concentric relation and in sliding engagement with 50 each other and forming the annular walls of a mixing chamber provided with main air-inlet and mixture-outlet openings, said valve members having coacting auxiliary air-inlet ports forming an auxiliary inlet passage for 55 high-speed air adapted to communicate with the mixing chamber, and having other coacting ports forming an auxiliary inlet passage for low-speed air, adapted to be closed when the auxiliary passage for admitting 60 high-speed air and the main air-inlet passage are closed, one of said tubular valve members being rotative with respect to the other for changing the width and effectual area of the openings formed by said auxiliary 65 ports, and the other of said tubular

valve members being movable endwise in opposite directions to open and close the passages formed by said auxiliary and main air-inlet ports, a nozzle having a combustible fluid supply passage communicating with 70 the mixing chamber, a throttle valve for opening and closing the mixture-outlet opening, a link having one end pivotally connected with the endwise movable tubular valve member and having its opposite end pivotally connected with said throttle valve, means for operatively connecting the mixture-outlet passage with an engine, and means for operating the throttle valve and endwise movable tubular valve member. 75

20. In a carbureter, the combination of a main casing, a pair of tubular valve members mounted in the main casing in concentric relation and in sliding engagement with each other and forming the walls of a mixing chamber having main air-inlet and mixture-outlet openings, one of said tubular valve members being rotative with respect to the other and having an auxiliary air-inlet passage adapted to communicate with 80 the mixing chamber, for admitting an auxiliary current of high-speed air to said chamber, and the other of said tubular valve members being movable endwise in one direction into position to close said auxiliary air-inlet passage and in an opposite direction into position to open said port, an annular flange upon the lower end of the endwise movable valve member and movable with the latter toward and from the lower open end 85 of the rotative valve member, for opening and closing the main air-inlet opening, a throttle valve for opening and closing the mixture-outlet opening, and manually operable mechanism for moving the endwise 90 movable tubular valve member in one direction, to open the main air-inlet port and the auxiliary port for admitting high-speed air simultaneously with the movement of the throttle valve to open position, said manually 95 operable mechanism acting to move the endwise movable valve member in a direction to close the main air-inlet passage and said auxiliary air-inlet port for admitting high-speed air with the movement of the 100 throttle valve to closed position, said tubular valve members being provided with coacting ports adapted to form an auxiliary open inlet passage for low-speed air, when the main air-inlet passage and the inlet passage for 105 auxiliary high-speed air are closed. 110

21. In a carbureter, the combination of a main casing, a pair of hollow cylindrical valve members mounted in the main casing and forming the walls of a mixing chamber 115 having a main air-inlet opening at its bottom portion and a mixture-outlet opening at the upper portion of said chamber, said cylindrical valve members having adjacent peripheral auxiliary air-inlet ports inter- 120 125

mediate the main air-inlet opening and the mixture-outlet opening and adapted to communicate with the mixing chamber formed by said cylindrical valve members, means 5 for rotating the outer cylindrical valve member to different adjusted positions, for changing the area of the auxiliary air-inlet opening formed by said ports, means for moving the inner cylindrical valve member 10 endwise for increasing and diminishing the area of said ports in a direction longitudinally of said valve members, and an annular flange upon the lower end of and movable upward and downward with the endwise 15 movable cylindrical valve member, for increasing and diminishing the area of the main air-inlet opening.

22. In a carbureter, the combination of a main casing, a pair of hollow cylindrical, 20 valve members mounted in the main casing and forming the walls of a mixing chamber having a main air-inlet opening at its bottom portion and a mixture-outlet opening at the upper portion of said chamber, said 25 cylindrical valve members having adjacent peripheral ports intermediate the main air-inlet opening and the mixture-outlet opening and adapted to communicate with each other and with the mixing chamber formed 30 by said cylindrical valve members, means for rotating the outer cylindrical valve member to different adjusted positions, for changing the area of the auxiliary air-inlet opening formed by said ports, means for 35 moving the inner cylindrical valve member endwise for increasing and diminishing the area of said ports in a direction longitudinally of said valve members, an annular flange upon the lower end of and movable 40 upward and downward with the endwise movable cylindrical valve member, for increasing and diminishing the area of the main air-inlet opening, a manually operable throttle valve for controlling the mixture- 45 outlet passage, and means for operatively connecting the throttle valve with the endwise movable cylindrical valve member.

23. In a carbureter, the combination of a main casing, a pair of tubular valve mem-

bers mounted in the main casing in concentric relation and in sliding engagement with each other and forming the walls of a mixing chamber having main air-inlet and mixture-outlet openings at opposite ends of said valve members, one of said tubular valve 55 members being rotative with respect to the other and having an auxiliary air-inlet port adapted to communicate with the mixing chamber, for admitting auxiliary high-speed air, and the other of said tubular valve members being movable endwise in one direction into position to close said auxiliary air-inlet port and in an opposite direction to open said port, an auxiliary air-inlet passage leading into the mixing chamber for admitting an auxiliary current of air for low-speed operation, when the auxiliary inlet passage for high-speed air is closed, an annular flange upon the lower end of the endwise movable valve member and movable 60 with the latter toward and from the lower open end of the rotative tubular valve member, for opening and closing the main air-inlet opening, a throttle valve for opening and closing the mixture-outlet opening, and 75 manually operable mechanism connected with the endwise movable tubular valve member and acting to move the latter endwise in one direction to open the main air-inlet passage and the auxiliary inlet passage 80 for high-speed air, and close the auxiliary inlet passage for low-speed air with the movement of the throttle valve to open position, and acting to move said endwise movable valve member in an opposite direction 85 to close the main air-inlet passage and the auxiliary inlet passage for high-speed air and open the auxiliary passage for low-speed air, with the movement of the throttle valve toward closed position.

In testimony that I claim the foregoing as my invention I affix my signature, in the presence of two witnesses, this 27th day of January, A. D. 1913.

WILLIAM OTTAWAY.
